UNITED STATES PATENT OFFICE.

STEPHEN MATHIAS SMITH, OF BOISE, IDAHO.

PROCESS OF SAVING THE VALUES OF CONCENTRATES AND SLIMES.

No. 895,509.

Specification of Letters Patent.

Patented Aug. 11, 1908.

Application filed June 4, 1903. Serial No. 160,067.

To all whom it may concern:

Be it known that I, STEPHEN MATHIAS SMITH, a citizen of the United States, residing at Boise city, in the county of Ada, State 5 of Idaho, have invented certain new and useful Improvements in Processes of Saving the Values of Concentrates and Slimes; and I do hereby declare the following to be a full, clear, and exact description of the invention, such 10 as will enable others skilled in the art to which it appertains to make and use the same.

My invention while relating generally to the treatment of ores for the extraction therefrom of the precious materials contained 15 therein, is directed more particularly to the treatment of tailings, or concentrates for the recovery of values escaping from the concentrator or equivalent mill appliance, an object of my improved process being the separation 20 from the partly worked ore-bearing materials of all of the contained values regardless of the character or condition of such materials or of the degree of fineness of the valuable product or products. It will be understood 25 however that my improved process is equally applicable to the treatment of ore-bearing materials in their initial state or condition, hence the hereinafter stated specific adaptation is not to be regarded as a limitation. 30

The nature of my improved process and the simplicity of construction of apparatus necessary for carrying the same into effect, renders it especially adaptable for the treatment 35 of low grade ores and ores which are largely composed of slimes, which ores have heretofore been regarded as practically valueless by reason of the great expense attending their reduction and the inefficiency of the 40 processes or apparatus employed.

A further difficulty encountered in the treatment of certain kinds of ores is in the elimination of arsenic, antimony, sulfur and other elements which, as is well known, have 45 a detrimental effect on the ores, and in many instances practically defeat the purpose of the process or action of the apparatus employed. My improved process is especially designed with the view to overcoming this 50 last named difficulty, the objectionable elements being entirely eliminated at one stage of the process.

Another advantage possessed by my improved process is economy in the use of water. In carrying the process into effect, the 55 same body of water may be repeatedly used,

thereby rendering the process adaptable to mining districts in which a scarcity of water prevails.

The nature of my improved process will be 60 readily comprehended reference being had to the following detailed description and to the accompanying drawing which illustrates by a perspective view an apparatus capable of carrying the process into effect. 65

Referring to the drawing by numerals, 1 designates a pipe for conveying to the apparatus the water and material discharged from the concentrator, crushing machinery or other appliance, a preferred way being to 70 connect said pipe with a suitable hopper at the overflow or tailings end of the concentrator. The pipe delivers the water and material into one end of a washing and settling tank 2 which is divided transversely by 75 partitions 3 into compartments and is provided near its opposite end with a lower discharge opening 4, for gangue, and with an upper discharge spout 5 for the lighter materials, such as slimes, arsenic, antimony, sulfur and the values. The water and material is delivered by the pipe 1 into the first compartment and overflows therefrom into the next compartment, and so on, until the tank 80 is filled, whereupon the pipe may be brought into position to fill a second tank 6 arranged 85 alongside the tank 2 and similarly provided with compartments formed by partitions 7 and with lower and upper discharges 8, 9. Obviously the number of tanks employed 90 will depend upon the desired capacity of the apparatus. The function of these tanks is to separate the gangue, slimes and values, the former settling to the bottoms of the compartments, and the slimes and values being 95 discharged through the spouts 5, 9.

The gangue, before its withdrawal from the tanks, is thoroughly washed and rinsed to effect the recovery of any remaining values, this being accomplished by water supplied under pressure from a penstock 10, through a preferably flexible tube or hose 11 and through nozzles 12, 12 at openings in a pipe 13 arranged above and longitudinally of the tanks. Said pipe is connected centrally 100 with the hose by a valved pipe 13'. As shown, I prefer to employ two nozzles for each compartment, the nozzles of a pair inclining in opposite directions, and to facilitate the stirring, washing and rinsing operation, the pipe is vibrated by hand, suitable means, for example the handle 14, being pro- 105 110

vided for the purpose. The nozzle equipped pipe 13 is shiftable from one tank to the other, whereby interruptions in the operation are avoided, the hose 11 being of the proper length to allow of the pipe being brought over the tank 2. In the step of treating the gangue for the recovery of the values remaining therein, the material is violently agitated and is brought into a state of suspension in the water whereby its discharge through the openings 4, 8 is facilitated. The washed and rinsed gangue falls from the openings into a trough 15 between the tanks and from thence is conveyed away in any suitable manner.

15 The lighter materials discharging from the tanks are conducted by inclined troughs 16 to settling tanks 17, 18, of relatively large capacity, the function of which is to separate the deleterious substances or elements, such as arsenic, antimony and sulfur from the slimes and values. Preferably, the tanks 17 and 18 afford the support for the elevated tanks 2, 6, though this is not an essential arrangement. In the tanks 17, 18, the slimes and values are caused to settle to the bottom, the arsenic, antimony and sulfur rising to the surface where they are skimmed and run into discharge spouts 19, 20 and are conveyed therefrom to any point outside of the mill.

25 30 The separation of the slimes and values from the objectionable substances named, is effected by heat applied to the contents of the tanks 17, 18, by pipes in which the heating medium, preferably hot water, is caused to circulate.

Referring to the heating means, 21 denotes a pipe leading from the lower end of the penstock to furnaces 22, 23, said pipe being branched, as at 24, 25, and each branch 40 leads to its respective furnace and is provided with a controlling valve. Each of said pipes is connected by suitable couplings, including reducers, with two pipes 26, 27 of equal capacity and of relatively lesser diameter, whereby to diminish the flow, which smaller pipes enter the furnace and are bent, as shown, to provide the proper heating surface to bring the water therein to the required temperature. The pipes 26, 27 commonly connect with a valved pipe 28 which enters the respective tank 17 or 18, at the bottom thereof, and is divided, as at 29, and bent to zig zag form to provide a large heating surface for raising the temperature of the 45 contents of the tank to effect the separation of the arsenic, antimony and sulfur from the slimes and values, as above stated. The pipe extensions 30, 30 of the pipe 28, finally extend vertically and project above the top 55 of the tank, as at 31, where connections may be made with the respective settling tank, or with a sump tank 32 located adjacent to and below the settling tank.

33, 34 are drying tanks for the concentrates. Said tanks are supported respec-

tively on the furnaces 22, 23 whereby they receive heat from the latter, but to obtain the requisite degree of temperature, zig zag heating pipes 35 are arranged in the tanks, the heating medium being supplied from the pipes 28 by a valved connecting pipe 36. The hot water, after traversing the pipes 70 discharges into the settling tanks from pipes 37, 37.

It will be noticed that I have described 75 the use of hot water as a heating medium for the separating tank. My purpose in using hot water is to give me a heating medium which can be readily controlled and which will heat up the mixture in the tank without causing the same to boil. It will be further noticed that by the use of a heat which does not produce boiling, that the mixture in the tank is heated up without the same being agitated. While I have described the use of 80 hot water as a heating medium, it is to be understood that any other heating agent 85 may be used, if found desirable.

In practice, initial separation of the slimes, 90 values and deleterious substances from the gangue, having been accomplished, in the manner stated, by the employment of the tanks 2 and 6 and the water jets, the gangue is thoroughly washed and rinsed to effect the separation of any values remaining therein, 95 and the separated materials are collected in the tanks 17, 18, where, by the application of heat, the arsenic, antimony and sulfur are caused to rise to the surface and are skimmed off. The clear water is then drawn off from the tanks 17, 18 at different levels, plugged 100 outlets 38, 38 being successively opened, beginning at the uppermost one and ending with the lower one which latter is provided with a screen 39 to strain the water from 105 the slimes. The slimes remaining in the tanks are then dried by the application of heat from the pipes 28, 29 and 30 and are removed through door controlled openings 40 in the inner walls of the tanks. The slimes 110 are here loaded on cars which travel on a track 41 leading to the sacking house or smelter, as the case may be.

The sump tank receives the clear water 115 from the tanks 17 and 18 and also, if desired, the hot water discharging from the pipes 31. At 42 is a plugged opening by which to empty the tank when desired. A conveyer is provided to elevate the water from the sump tank to a pressure tank 43 supported by framing 44 at a suitable height and from the bottom of which leads the penstock 10. The conveyer consists of an endless belt 45 carrying at intervals buckets 46 and passing around a lower driven wheel in 120 the sump tank and around an upper wheel 47 supported above and at one side of the pressure tank 43. The inner wall of each bucket is relatively longer than the outer 125 wall, and said buckets discharge their con- 130

tents immediately after they pass the top of the upper wheel 47, into a hopper 48 having a lower opening 49 from which the water discharges into the pressure tank. The 5 buckets are each provided at their discharge end with an inwardly bent extension 50, the angle of which is approximately eight degrees, for retaining the water in the bucket until the point of discharge is reached. It 10 will be understood that any sediment entering the sump tank is allowed to settle to the bottom whereby only clear water is elevated to the pressure tank. The tanks 33, 34 are employed for drying the concentrates 15 collected from the concentrating tables below the battery, the heat being, as above stated, derived from their proximity to the furnaces and from the heat radiating pipes 35.

20 It will be observed that all of the conducting pipes are equipped with valves whereby the operation of the apparatus is under complete control. The number of tanks employed will depend upon the desired capacity 25 of the apparatus, and the number shown is not, therefore, to be regarded as a limitation.

I claim as my invention—

1. The process of recovering slimes from 30 water in which they are suspended, and separating arsenic, sulfur or antimony from the slimes, which consists in placing the water containing the slimes in a receptacle and uniformly heating the same without boiling or 35 agitation, whereby the slimes are caused to precipitate after the arsenic, sulfur or antimony has been separated therefrom.

2. The process of recovering slimes from 40 water in which they are suspended, and separating arsenic, sulfur or antimony from the slimes, which consists in placing the water containing the slimes in a receptacle and uniformly heating the same without boiling or 45 agitation, whereby the slimes are caused to precipitate after the arsenic, sulfur or anti-

mony has been separated from the slimes, and then drawing the water free from the slimes from the receptacle.

3. The process of separating ore slimes from crushed ore or gangue and recovering 50 the slimes, which consists in introducing the crushed ore or gangue containing the slimes into a receptacle, subjecting the material therein to the action of the water, whereby the slimes will be separated from the crushed 55 ore or gangue and will flow out over the edge of the receptacle with the water, the slimes by the addition of washing water being greatly diluted, conveying the water carrying the slimes in suspension into a receptacle, 60 and uniformly heating the same throughout without boiling, agitating or boiling currents in the water containing the slimes, whereby the slimes are caused to precipitate without disturbance, and then drawing off the water 65 free from slimes from the receptacle.

4. The process of recovering slimes from water in which they are suspended, and clarifying the water which consists in placing the water containing the slimes in a receptacle 70 and heating the same without boiling or agitation, whereby the slimes are caused to precipitate and the arsenic, antimony or sulfur compounds which may be contained in the slimes caused to rise to the surface, removing 75 the elements on the surface of the water, and drawing off the water from the receptacle free from slimes and foreign matter.

5. The process of settling slimes and purifying the water in which they are suspended, 80 which consists in subjecting the liquid carrying the slimes to the action of heat, whereby the slimes are precipitated and the impurities in the liquid caused to rise, removing the impurities from the top of the liquid, and decanting the liquid from the settled slimes. 85
